M. LEBLESON

STRAINER AND STOPPER FOR PIPES

Filed May 10, 1922

FIG. 1

FIG. 2

FIG. 3

INVENTOR.

Minnie Lebleson

BY
M. J. O'Neill
ATTORNEY.

UNITED STATES PATENT OFFICE.

MINNIE LEBLESON, OF GUTTENBERG, NEW JERSEY.

STRAINER AND STOPPER FOR PIPES.

Application filed May 10, 1922. Serial No. 559,822.

To all whom it may concern:

Be it known that I, MINNIE LEBLESON, a citizen of the United States, and a resident of Guttenberg, in the county of Hudson and

5 State of New Jersey, have invented certain new and useful Improvements in a Strainer and Stopper for Pipes, of which the following is a full, clear, and exact specification.

This invention relates to a class of devices 10 adapted to be used in conjunction with wash tubs, sinks and the like.

My invention has for its object primarily to provide a strainer and stopper designed to be applied to the discharge pipe of a stationary wash tub, or sink or other receptacle so that water or other fluid may be drained therefrom as well as straining foreign material which may be contained in the fluid to prevent the material from 15 clogging the passage of the pipe, and which is of a form adapted to permit the entrance to the pipe to be closed when desired for accumulating a quantity of fluid in the receptacle. The invention contemplates mainly

20 the provision of a hollow body having an annular upstanding wall with an open top, and having on its lower end a perforated bottom. The hollow body may be of a size adapted to be removably held over the entrance of the pipe of a stationary wash tub, sink or other receptacle so that when it is desired to drain the receptacle of water or other fluid it will flow through the perforations into the body and into the pipe.

25 Should the fluid contain foreign material it will be strained during the flow of the fluid through the perforations, and a separate stopper element is provided for removable insertion into the body to close ingress 30 into the pipe to allow a quantity of the fluid to be accumulated in the receptacle.

A further object of the invention is to provide a strainer and stopper of a simple, efficient and durable construction which may 45 be made in any appropriate shape and size.

With these and other objects in view, the invention will be hereinafter more fully described with reference to the accompanying drawing forming a part of this specification 50 in which similar characters of reference indicate corresponding parts in all the views, and will then be pointed out in the claims at the end of the description.

In the drawing, Figure 1 is a fragmentary

view, showing a top plan of a stationary 55 wash tub or sink with one form of strainer and stopper embodying my invention applied thereto.

Fig. 2 is an enlarged fragmentary view, showing an enlarged section taken through 60 the form of the device shown in Fig. 1 and which also shows section taken through part of the tub and through part of its discharge pipe, and

Fig. 3 is an enlarged fragmentary view, 65 showing a detail section taken on the line 3-3 of Fig. 2.

The strainer and stopper has a hollow body 10 with an upstanding annular wall 11, and on the lower end of this wall is a 70 bottom 12, while the upper end of the wall is open to provide an entrance 13. When the device is of a form adapted to be used in a stationary wash tub or sink or other receptacle, as 14, having a discharge pipe, as 75 15, with cross-bars, as 16, provided in its mouth, the wall 11 of the hollow body 10 is made larger in diameter than the diameter of the plate. The central part of the 80 bottom 12 may then be concaved, as at 17, with spaced interstices or perforations, as 18, while the edge portion, as 19, of the bottom may be imperforate as well as being flat. Also in the annular wall 11 of the body 10 in spaced proximity to the bottom 12 may 85 be one or more rows of perforations, as 20, and on opposite parts of the underside of the bottom 12 are depending clips, as 21 and 22, for serving as means to removably fasten the body to the cross-bars 16 of the pipe 15. 90

The clips 21 and 22 are of corresponding shapes and sizes; and each clip is preferably of the form of a hook having a shank portion 23 with an angularly bent part or finger, as 24. These 95 clips or hooks are relatively arranged so that their fingers 24 are disposed in opposite directions, and both clips are of sizes so that when the body 10 is arranged over the pipe with its bottom positioned on the cross-bars 16 the fingers of the clips or hooks will engage the cross-bars when the body is partially rotated accordingly. The body will thereby be detachably fastened over the pipe. When water is delivered into the receptacle 14 and drained into the pipe 15 the water or other fluid will flow into the body through the perforations 20, and then flow 100 105

through the perforations 18 of the bottom 12 into the discharge pipe 15. Foreign solid substances which may be mixed with the water will then be strained to avoid passage 5 into the pipe which in turn will prevent clogging of the pipe.

Serving to permit the passage of the fluid into and out of the body 10 to be cut-off when desired, a stopper, as 25, is provided.

- 10 The stopper 25 is in the form of a cap having a top plate 26 with a downwardly protruding annular wall 27 of a diameter adapted to be inserted in the hollow body 10 through its entrance 13 as well as removal-
15 bly and snugly fitting the wall 11 of the body. The wall 27 of the cap is also of a length so that when the cap is inserted in the body 10 the free edge of the cap will abut against the flat edge portion 19 of the
20 bottom 12 of the cap so as to close the passage through the perforations 20 of the hollow body for preventing the flow of fluid into the discharge pipe through the body 10, and the stopper or cap 25 may be con-
25 nected to the body by a flexible line or chain
26^a having its ends attached to the body and to the cap.

In the foregoing description, I have embodied the preferred form of my invention, 30 but I do not wish to be understood as limiting myself thereto, as I am aware that modifications may be made therein without departing from the principle or sacrificing any of the advantages of this invention, 35 therefore, I reserve to myself the right to make such changes as fairly fall within the scope thereof.

Having thus described my invention, I

claim as new and desire to secure by Letters Patent:

1. As an article of manufacture, a strainer and stopper for pipes, formed with a hollow body having an annular upstanding wall with an open top and having perforations in spaced proximity to its lower end, 40 a bottom on the lower end of the annular wall, having an imperforate flat edge portion and having a perforated concaved central portion, and hooks on the bottom of the body for releasably engaging a crossbar in the entrance of the pipe by partially rotating the body.

2. As an article of manufacture, a strainer and stopper for pipes, formed with a hollow body having an annular upstanding wall with an open top and having perforations in spaced proximity to its lower end, 45 a bottom on the lower end of the annular wall, having an imperforate flat edge portion and having a perforated concaved central portion, hooks on the bottom of the body for releasably engaging a crossbar in the entrance of the pipe by partially rotating the body, 50 a separate stopper element adapted to be removably fitted in the open end of the body for cutting-off ingress to the body by closing the passages of the spaced perforations in the wall of the body, and a flexible line element having its ends attached to the body and to the stopper element.

This specification signed and witnessed this 9th day of May, A. D. 1922.

MINNIE LEBLESON.
